UNITED STATES PATENT OFFICE.

PATRICK J. MADDEN, OF CHICAGO, ILLINOIS.

PLUMBING-FIXTURE.

1,035,457.

Specification of Letters Patent. Patented Aug. 13, 1912.

Application filed July 27, 1909. Serial No. 509,913.

To all whom it may concern:

Be it known that I, PATRICK J. MADDEN, a citizen of the United States, residing at Chicago, in the county of Cook and State 5 of Illinois, have invented certain new and useful Improvements in Plumbing-Fixtures, of which the following is a specification.

All of the several features of the invention are applicable to a lavatory and hence this embodiment of it is selected for the purposes of this application, but all or some one or more of its features are also applicable to other plumbing fixtures, such, 15 for instance, as water closets, flushing tanks, urinals, sinks, drinking fountains, and others. Hence, while the following description will be confined to the several features of the invention as applied to a lavatory, 20 it is with the understanding that I reserve to myself the exclusive right to use its several features in connection with any plumbing fixtures for which they may be adapted.

The invention relates in part to means 25 for supporting the receptacle or fixture, proper; in part to an adjustable support, interposed between the receptacle and an ultimate or primary support, such as a wall, whereby the receptacle may be adjusted 30 horizontally, relatively to the wall; in part to means for adjusting a pipe to bring its vertically presented open end into register with the opening in the bottom of such an adjustable supported receptacle and holding 35 it fixedly in its adjusted position; and in part to the construction of the receptacle whereby it is particularly adapted for use as a lavatory.

The invention consists in the features of 40 novelty that are hereinafter described.

In the accompanying drawings, which are made a part of this specification: Figure 1 is a vertical central section of a lavatory embodying the invention, the section being 45 taken on the line 1—1, Figs. 3 and 4. Fig. 2 is a vertical section of a portion thereof on the line 2—2, Figs. 3 and 4. Fig. 3 is a horizontal section thereof on the line 3—3, Figs. 1, 2 and 4. Fig. 4 is a rear elevation 50 thereof. Fig. 5 is a vertical section, on a larger scale, of the parts accessory to the opening (in this instance the outlet opening) through a wall of the receptacle for the passage of water.

55 A represents the bowl proper of a lavatory, the bottom of which is provided near

the back with an opening a guarded by a strainer. Behind the back of the bowl is a vertical chamber A' which extends from the under side of the horizontal top slab A^2 at the back of the bowl downward to a level below the bottom of the bowl, and the bottom of this chamber is extended forward beneath the bowl to a point in front of the opening a to form a passage a' through 60 which the interiors of the bowl and the chamber are in constant open communication. The bowl A , the chamber A' and the passage connecting them taken together constitute what is herein called the "receptacle."

The bottom of the chamber A' (i. e. the bottom of the receptacle) is provided with an opening a^2 for the outlet of the contents of the receptacle. The circular wall of this 75 opening flares upward and outward, and on its under side the bottom of the receptacle is countersunk around the opening, the outer circular wall a^3 of the countersink being flared downward and outward, providing a shoulder presented inward, toward the opening. Within the opening is arranged a thimble comprising a flaring portion B and a cylindrical portion B' . The flaring portion is complementary to and bears 80 firmly upon the flaring wall a^2 of the opening and its inner flaring face affords a seat for the valve for controlling the opening. This valve consists of a rubber ring B^2 of appropriate shape surrounding a tube B^3 85 and held in place thereon by a nut B^4 having threaded engagement with the tube. The tube B^3 occupies the chamber A' and passes through an opening at the top thereof, its upper end being provided with a suitable knob for manipulating it. It performs 90 the double function of an overflow and a stem for the valve B^2 , in the customary manner. The cylindrical portion of the thimble extends into the countersink and is externally threaded. Onto it is screwed a ring C 95 which bears against the bottom of the countersink so that when screwed home it holds the thimble firmly in place and is itself firmly held in place by the thimble. The periphery of the ring is chamfered reversely to the flaring wall a^3 of the countersink to provide a shoulder, so that the two together form a groove of substantially V-shape in which fits one side of an elastic packing 100 ring D of substantially diamond shape in cross section. The other side of the pack-

ing ring fits in an annular V-shaped groove formed in a flange *e* carried by the vertically presented open end of a pipe *E*.

With the parts thus constructed and arranged, a water tight joint between the receptacle and pipe may be made by forcing them toward each other and compressing the packing ring *D*, and so far as the present invention is concerned, this may be done by any suitable means. The means shown in the drawings consists of a screw *F* engaging the pipe, a nut *F'* supporting the screw and a housing *A* supporting the nut, the housing being integral with the bowl, and so shaped as to cover the end of the pipe. With this arrangement, the pressure provided by tightening the screw reacts in opposite directions against the receptacle and pipe with a tendency to force them toward each other and compress the packing ring, but, the pipe being supported, (as presently described) so as to be incapable of any vertical movement, the tightening of the screw in fact draws the bowl downward toward the pipe. Thus the pipe may be made to support the receptacle, either wholly or partially. But the housing, the broad means for forming a tight joint between the pipe and the receptacle, and the means for supporting the receptacle, and preventing its upward displacement, form parts of the subject matter of my Patent No. 897,914, granted September 8, 1908, and are not claimed broadly in this application.

The particular means described in this application for coupling together and forming a tight joint between the pipe and the receptacle are not claimed in this application, but are made the subject of a divisional application, filed September 30, 1911, Serial No. 652,101.

The distance between the opening *a* of the receptacle and the wall *G*, or other primary support, is determined by the distance between said opening and the ground surface *a'* at the back of the housing *A*, and this latter distance varies more or less in different fixtures because of the impossibility of making, baking and grinding a number of earthenware fixtures with such accuracy and perfection that all of them will be exactly alike in their measurements. It therefore becomes necessary to provide means for adjusting the vertically presented open end of the pipe *E* relatively to the wall *G*, in order to bring it to register with the opening of the receptacle. To this end a nut *H* on an externally threaded horizontal portion *E'* of the pipe-section *E*, is adjusted to such position that when the open end of the pipe is in register with the opening of the receptacle, the nut bears against the outer face of the wall; an internally threaded pipe-section, *I*, fits, snugly, a horizontal opening through the wall and is screwed onto the threaded por-

tion *E'* of the pipe-section *E* until it compresses between its end and the nut *H* an elastic gasket, *J*, and a nut *K* is turned onto the externally threaded projecting end of the pipe-section *I* until it bears firmly against the rear face of the wall, whereby the wall is firmly clamped between the two nuts and the pipe comprising the pipe-sections, *E* and *I*, firmly held against either vertical or horizontal movement relatively to the wall.

The vertically presented end of the pipe *E* is provided with a projecting annular lip *e'* and the ring *C* is countersunk to provide an annular shoulder *c* adapted to encircle and engage the lip and thereby aid the packing ring *D* in preventing the receptacle from being drawn outward relatively to the end of the pipe or relatively to the wall.

In my patent aforesaid, the housing *A* lies beneath and joins the bottom of the bowl proper and the ground vertical surface at the back of the housing is flush with the ground surface of a shallow rib or raised portion following the contour of the back of the bowl, but in the present case, the presence of the chamber *A'*, and other parts hereinafter described, behind the bowl makes it desirable to carry the sides of the housing upward to the under side of the horizontal top slab *A* which extends rearward from the bowl. The housing thus constructed, *i.e.* joining the top slab and extending downward to a level far below the bowl, and joining the back of the bowl and extending rearward to a bearing against the wall and also extending beneath and joining the bottom of the bowl, serves to very materially strengthen the fixture and prevent its being distorted or warped by handling or baking. The fixture is still further strengthened by a hollow rim *A* which surrounds the bowl and is continued rearward, past the back of the bowl, to the wall, where it is provided with a ground surface *a'* which is flush with the surface *a'* opposite the slab *A* and with a ground surface *a''* on a shallow rib or raised portion *A* which follows the top and sides of a vertical back or wall-slab *A*, rising from the top slab *A*. The fixture is still further braced and strengthened by horizontal webs *A* which join the back of the bowl and extend from the sides of the housing *A* to the rearwardly extending portions of the hollow rim. The several parts going to make up the fixture proper are designated by the letter *A* or *A* with an exponent and all of them are molded of potters' clay or other suitable material and seamed together so that when baked all parts of the fixture proper are integral.

At the top side of the back or wall slab *A* the rib or raised portion *A* is undercut to provide an overhanging lip *A*, the shoulder resulting from the sloping inner face of

which is adapted to rest upon a correspondingly inclined seat on a bracket L carried by a plate M secured to the wall G, a rubber packing N being interposed between the bracket and shoulder for the double purpose of lessening the liability to breakage and affording a yielding support for aiding the pipe E I in supporting the fixture. This bracket L, (or these brackets where more than one is used, as in the present case, where one is used on each side of the center of the receptacle) not only supports, or aids in supporting, the fixture, but by reason of the engaging inclined faces of the shoulder and bracket aids the pipe E I and the coupling between the pipe and the receptacle in preventing the latter from moving away from the wall. The accomplishing of both of these results is further contributed to by a second bracket O carried by the plate M, a bolt P passing through a slot o in the bracket and projecting into a socket a² in the bottom web A¹, and two nuts Q and R on the bolt. The head of the bolt bears against the underside and the nut Q bears against the upper side of the bracket O, so as to clamp the bracket between them and thereby hold the bolt fixedly in place after it has been adjusted in the slot o to such position that its upper end occupies the socket a². The nut R is then turned up to the bolt until it bears upon the underside of the web A¹, through the medium of an elastic packing S with sufficient force to at least assist in supporting the fixture. Thus the fixture is carried by five vertically yielding supports located at three different levels. So far as the position of these supports relatively to the face of the wall or the ground surfaces at the back of the fixture are concerned, the upper supports engaged sloping surfaces on the back of the fixture, the intermediate supports are adjustable by reason of the slots o, and the lower support is adjustable by reason of the horizontal adjustability of the pipe E.

It will be understood that the ground surfaces a⁴ at the back of the receptacle should bear firmly against the wall G, but in the manufacture of the parts there is more or less variation or irregularity in the contacting surfaces of these parts, and it is in order to compensate for these variations or irregularities that the intermediate supports are made adjustable horizontally, and that the pipe E I is also made horizontally adjustable. In the assembling of the parts the receptacle is first placed firmly against the wall, and brought to a bearing upon the bracket L; the bolt P is then adjusted horizontally to properly enter the socket a² and by engaging the rear wall of said socket prevent the receptacle from moving outward, horizontally, away from the wall, sufficient clearance being left between the nut R and the

receptacle to allow for the compression of the several elastic packings; the pipe E I is then adjusted horizontally to bring its open upper end into register with the opening a² through the bottom of the receptacle, after which the nuts H and K are tightened up to hold the pipe against horizontal movement; the screw F is then tightened up to draw the receptacle down, simultaneously compressing the several gaskets or elastic packings, and seating the receptacle upon its supporting brackets, so that it is held against upward displacement. In order to accomplish the first adjustment of the parts more or less trying, by placing the parts in position and removing them and resetting the several adjusting nuts will be necessary, but when the proper adjustment is once accomplished the receptacle may be removed and put in place without disturbing the adjusting devices.

The subject matter of the present application was shown, described and claimed, substantially, by an application filed by me December 21, 1907, under Serial No. 407,604.

What I claim as new and desire to secure by Letters Patent is:

1. In a plumbing fixture, the combination with the fixture proper having at its back a downwardly presented bearing surface and a wall against which the back of the fixture bears, of a support for the fixture, said support having a bracket carried by the wall, and having a slot elongated transversely to the general plane of the wall, a bolt carried by the bracket, and laterally adjustable in said slot toward or from the wall, and a nut carried by the bolt and interposed between said bracket and the fixture, said nut being adapted to engage the downwardly presented bearing surface on the fixture.

2. In a plumbing fixture the combination with the fixture proper having at back a downwardly presented bearing surface, and a wall against which the back of the fixture bears, of a support for the fixture, said support having a bracket independent of the fixture carried by the wall, said bracket having an opening through it, a bolt passing through said opening, an adjustable nut arranged on the bolt between the bracket and the downwardly presented shoulder of the fixture, said nut being adapted to engage the top side of the bracket, and a second adjustable nut similarly arranged on the bolt and adapted to engage the downwardly presented bearing surface of the fixture.

3. In a plumbing fixture, the combination with the fixture proper having shoulders presented downward, at the back thereof, and a wall against which the back of the fixture bears, of a plurality of supports for the fixture, each of said supports having a plate secured to the wall, two brackets lo-

cated one above the other carried by each of said plates, the upper brackets engaging the upper shoulders on the fixture and means interposed between the lower brackets and the lower shoulders on the fixture for supporting the fixture, said supporting means being vertically adjustable independently of each other.

4. In a plumbing fixture, the combination
10 with the fixture proper having, at back a
downwardly presented bearing surface and
a wall against which the back of the fixture
bears, of means for preventing the fixture
from being moved outward, away from the
15 wall, said means having a bracket carried
by the wall and a part carried by the bracket
and engaging said downwardly presented
bearing surface, said part being adjustable
horizontally toward and from the wall and
20 also adjustable vertically.

5. In a plumbing fixture, the combination with a supporting wall, and a receptacle, having at its back a surface adapted to bear against the wall and having through its bottom an opening for the passage of water, of a pipe having a vertical end presented upward and registering with the opening of the receptacle, means interposed between the wall and the receptacle for supporting the latter, said means being horizontally ad-

and the *lungs* were *swollen* and *distended* with *air*, so that the *breath* was *short* and *labored*. The *liver* was *swollen* and *distended* with *air*, so that the *abdomen* was *swollen* and *distended*. The *liver* was *swollen* and *distended* with *air*, so that the *abdomen* was *swollen* and *distended*. The *liver* was *swollen* and *distended* with *air*, so that the *abdomen* was *swollen* and *distended*.

justable for bringing the back of the receptacle to a firm bearing against the wall, means for horizontally adjusting the pipe relatively to the receptacle and holding it in its adjusted position, and means for forcing the pipe and receptacle toward each other, relatively. 35

6. In a plumbing fixture, the combination with a wall and a receptacle having at its back a surface bearing against the wall and having through its bottom an opening for the passage of water, of a horizontally adjustable pipe having its open end presented upward and registering with the opening of the receptacle, means for forming a tight joint between the receptacle and pipe and preventing the horizontal movement of the receptacle relatively to the pipe, means for holding the pipe in its horizontally adjusted position and preventing its horizontal movement relatively to the wall, and a support carried by the wall and engaging the receptacle, said support being horizontally adjustable, whereby the receptacle may be adjusted relatively to the wall. 40 45 50 55
